ABSORPTION REFRIGERATING SYSTEM

Curtis C. Coons, North Canton, Ohio, assignor to
 The Hoover Company, North Canton, Ohio, a
 corporation of Ohio

Application November 13, 1935, Serial No. 49,449

30 Claims. (Cl. 62—119.5)

This invention relates to continuous absorption refrigerating apparatus and more particularly to that type in which an inert gas is employed and in which a compound or two stage boiler is used.

In accordance with the present invention, the compounding of the boiler system is accomplished in various ways, and a new boiler construction is provided so as to effect certain improvements 10 in operation and efficiency or otherwise vary the operating conditions of refrigerating apparatus having compound boiler system.

Accordingly, it is one object of the invention to provide an absorption refrigerating apparatus 15 with a novel compound boiler system.

It is another object of the invention to provide an improved boiler structure adapted for use in an absorption refrigerating system, using inert gas and of the compound type.

It is another object of the invention to provide means for maintaining the proper temperatures in both the main boiler and the auxiliary boiler of the compound boiler system adapted for use in an absorption refrigerator.

Other objects and advantages reside in certain novel features of the arrangement and construction of parts as will be apparent from the following description taken in connection with the accompanying drawings, in which

Figure 1 is a diagram of a continuous absorption refrigerating system constructed in accordance with one embodiment of the invention, certain of the parts being cut away to better illustrate the construction;

Figure 2 is a vertical cross sectional view of a fragment of the absorber used in the arrangement of Figure 1 and showing the construction of a liquid seal incorporated therein;

Figure 3 is a vertical cross sectional view of the pumping means employed in the arrangement of Figure 1.

Figure 4 is a transverse cross sectional view of the liquid pumping means shown in Figure 3, the view being taken on the line 4—4 of Figure 3.

Figure 5 is a vertical cross sectional view of the boiler system used in the arrangement of Figures 1, 6 and 7;

Figure 6 is a diagram of a continuous absorption refrigeration system illustrating another embodiment of the invention, a portion of the absorber being cut away to show the internal construction;

Figure 7 is a diagram of still another embodi-

ment of the invention, one of the parts being cut away to show the internal construction.

Figure 8 is a vertical cross sectional view of the absorber used in the arrangement of Figure 7, and

Figure 9 is a diagram of still another embodiment of the invention, certain of the parts being cut away to show the internal construction.

Referring to the drawings in detail, and first to the arrangement of Figure 1, it will be seen 10 that a continuous absorption refrigerating apparatus has there been illustrated. This apparatus includes a condenser C, an evaporator E, an absorber system, which in reality consists of two absorbers A₁ and A₂, a boiler system which 15 in reality consists of two boilers B₁ and B₂, a rectifier R and pumping means marked P, together with various conduits interconnecting these parts as shown to form the complete system.

The boiler system is shown in detail and enlarged in Figure 5. In constructing this boiler system, three concentric sections of pipe marked 20 11, 12, and 13, are welded to end plates of annular shape, marked 14 and 15. Each of the 25 plates 14 and 15 has a central opening through which the central pipe 11 passes so that the inside of the pipe 11 acts as a flue for the heating of the boiler, suitable heating means, such as a gas flame 16 being provided therein.

The boiler B₁ is formed by the concentric pipes 11 and 12 and the end plates 14 and 15. This boiler is thus simply an annular chamber immediately adjacent the heating flue 11. The lower end of the boiler B₁ is connected to the top of the 35 boiler B₂ by means of a conduit 17 which passes through the upper part of the pipe section 12 and is preferably provided with a slight hook at its upper end. The conduit 17 is not a vapor lift pump, but is simply a means for conveying liquid from the lower part of the boiler B₁ to the top of the boiler B₂. If desired this conduit may pass outside of the boiler B₁, the arrangement illustrated being desirable, however, in that it provides a more compact assembly.

The boiler B₂ is formed by the pipes 12 and 13 and the end plates 14 and 15. The outer boiler B₂ is intended to have inert gas therein and it is intended that refrigerant vapor be generated from absorption liquid therein into 50 the inert gas. In order to facilitate this action, a number of baffle plates 18 are provided in the holder chamber B₂, these baffle plates having openings 19 therein arranged in staggered relation on opposite sides of the chamber. It 55

will be understood that the baffle plates 18 are annular in shape, like the boiler B₂.

The main boiler B₁ is connected to a rectifier R by means of a conduit 21 welded to its upper end. The top of the rectifier R is connected to the condenser C by the conduit 22, this conduit being like that in any continuous absorption refrigerating system for conveying refrigerant from the rectifier to the condenser. As the refrigerant condenses in the condenser C it flows through the conduit 23 into the evaporator E. The evaporator may be of conventional construction and have a number of baffle plates therein for causing the refrigerant supplied thereto to evaporate into inert gas therein.

The absorber system may be similar to that disclosed in the co-pending application of Rudolph S. Nelson, Serial No. 37,711 filed August 24, 1935, and entitled "Absorption refrigerating apparatus". As shown in Figure 1, it differs slightly in that it has a fan 24 mounted in the upper end thereof, and adapted to be driven by an electric motor 25. By means of a central partition 26, the cylindrical vessel which forms the two absorbers A₁ and A₂ is divided into two chambers. As shown in Figure 2, the partition 26 is provided with means for allowing liquid to pass from the upper absorber A₁ into the lower absorber A₂ through the U-shaped liquid conduit 27 which acts to provide a liquid seal. The lower end of the U-pipe 27 is disposed around a downwardly depending nipple 28 on the plate 26, so that in case a material difference in pressure exists between the absorber sections A₁ and A₂ gas may pass through the nipple 28 when the pressure becomes sufficient to break the seal of liquid formed in the liquid conduit 27.

In addition to the dividing partition 26 both sections A₁ and A₂ of the absorber system are provided with a number of baffle plates 29 for providing an extended surface therein which aids in bringing the absorption liquid and the gas to be absorbed into intimate contact. Each of the plates 29 is provided with an offset opening 30, these openings being staggered in the absorber so as to cause the liquid to flow in a tortuous path therethrough.

The upper absorber A₁ is connected to the evaporator by means of two inert gas conduits 31 and 32, portions of these conduits preferably being in heat exchange relation as illustrated. The conduit 31 connects the top of the evaporator to the bottom of the absorber A₁ while the conduit 32 connects the top of the absorber A₁ to the bottom of the evaporator. Circulation of inert gas between the evaporator and the absorber A₁ is caused by the fan 24 which discharges directly into the conduit 32 at the point where it is connected to the absorber A₁. Other gas circulating means may be employed without departing from the spirit of the invention.

A second inert gas circuit is provided between the absorber section A₂ and the auxiliary boiler B₂. For this purpose an inert gas conduit 33 is connected to the top of the absorber A₂ and to the bottom of the boiler B₂. A second gas conduit 34 connects the top of the boiler B₂ to the fluid circulating pump P which is in turn connected to the lower part of the absorber A₂ by means of the conduit 35. It will be noted that the point of connection of the conduit 35 to the absorber A₂ is such that the lower portion of the absorber A₂ may act as a reservoir for liquid.

Absorption liquid is circulated between the boiler system and the absorber system by means

of the fluid circulating device P. For this purpose a liquid conduit 36 is connected to the bottom of the auxiliary boiler B₂ and to the pumping device P. From this pumping device the conduit 37 conveys the absorption liquid to the top of the absorber A₁ and from there the absorption liquid flows by gravity downwardly through the absorber A₁, the liquid trickling over the baffle plates therein. It then flows through the liquid conduit 27 and on to the baffle plates in the absorber section A₂. After trickling downwardly over this set of baffle plates, the absorption liquid flows by gravity through conduit 38, a portion of which may be in heat exchange relation with the conduit 36 as illustrated, and into the rectifier R or, if desired, directly into the boiler B₁. Since the rectifier is connected to the boiler B₁ by the conduit 21, liquid supplied to the rectifier may flow downwardly through this pipe into the boiler section B₁ where it is heated and refrigerant generated therefrom. The liquid then flows from the boiler B₁ into the boiler B₂ through the conduit 17 as mentioned above.

The liquid and gas pumping device P is shown in detail in Figures 3 and 4. It consists of a cylinder 39 disposed in an inclined position with an electric motor 41 mounted on the upper end thereof. The motor drives a shaft 42 which is mounted in suitable bearings supported on end plates 43 and 44. The liquid pumping portion 30 may be like that disclosed in my co-pending application Serial No. 55,449 filed December 23, 1935. The arrangement here shown consists of means for forming a centrifugal pump chamber with a rotor therein. Two plates or housing 35 members 40 and 45 are secured in spaced relation by an annular ring 46 and bolts 47 to form the chamber. The shaft 42 extends centrally through this chamber and has a rotor 48 carried thereby. The rotor 48 is so cut as to provide a number of blades 49. The liquid enters the pump chamber through a small opening 50 in the plate 45 and near the lower end thereof. Liquid leaves the chamber through an opening 51 in the annular spacer ring 46, the opening 51 being arranged tangentially to the path of movement of the rotor 48 as shown in Figure 4.

The liquid supply conduit 36 which conveys liquid from the boiler B₂ to the pump P is connected to the lower side of the cylinder 39 so that the liquid can readily flow from the space above the plate 45 through the opening 50 and into the pump chamber proper. The discharge conduit 37 is connected to the pump chamber in line with the discharge opening 51 as shown in Figure 4.

The upper portion of the cylinder 39 contains a fan 52 for circulating the inert gas between the boiler B₂ and the absorber A₂. As best shown in Figure 3 the inert gas supply conduit 34 is connected to the cylinder 39 at a point near the top thereof, above a plate 53 which has an opening in the central portion thereof to provide a fan eye adjacent the rotor 52. Likewise, the gas discharge conduit 35 is connected to the cylinder 39 at a point opposite that of the location of the rotor 52 so that as the rotor revolves gas is blown into the conduit 35 by centrifugal action. A plate 54 is provided immediately beneath the fan 52 so as to co-operate with the plate 53 to provide a fan chamber.

For conducting any liquid which may find its way into the fan chamber the U-shaped conduit 55 is provided, and connected to the lower portion

of the fan chamber and to the cylinder 39 below the point of connection of the conduit 36.

The directions of flow of the fluids in the system are indicated, solid arrows showing direction of flow of the liquids and dash arrows showing the gases. Assuming that the system is charged with water as absorbent, ammonia as refrigerant, and nitrogen as inert gas and that after it is charged in accordance with known practices it is hermetically sealed, a number of cycles of fluid circulation will be set up when heat is applied to the boiler and when the motors 25 and 41 are energized.

Starting with the boiler B₁, the ammonia will pass through a cycle which may be called its main cycle in which it will be vaporized in the boiler B₁, flow through the conduit 21, the rectifier R and the conduit 22 as vapor, be condensed in the condenser C, evaporated in the evaporator E and pass with the nitrogen through the conduit 31 into the absorber A₁ where it will be absorbed in the aqueous solution therein, flow through the liquid conduit 27, downwardly through the absorber A₂, through the conduit 38, the rectifier, and thence through the conduit 21 back into the boiler B₁.

At the same time the ammonia will pass through a second cycle in which the ammonia will be generated and absorbed. Starting from the boiler B₂ the ammonia will be vaporized from the solution into the nitrogen in the boiler B₂ and flow through the conduit 34, the pump P and the conduit 35 into the absorber A₂ where it will be absorbed out of the nitrogen by the solution passing downwardly through the absorber A₂ and returned to the boiler B₂ through the conduits 38, the rectifier R, the conduit 21, the boiler B₁ and the liquid conduit 17.

At the same time the water or absorption solution will be caused to circulate from the boiler B₂ through the conduit 36, the pump P and the conduit 37 into the top of the absorber A₁. After trickling downwardly over the baffle plates in the absorber A₁ it will pass through the liquid conduit 27 and downwardly over the baffle plates in the absorber A₂. It then flows back to the boiler B₁ through the conduit 38, the rectifier R, and the conduit 21, and from the boiler B₁ it returns to the boiler B₂ through the conduit 17. Conduit 21 should be large enough that the vapor may flow up and the solution down without interference with each other therein. In the boiler B₂ the solution trickles downwardly over the baffle plates 18 and again enters the conduit 36 to complete the cycle.

At the same time two inert gas circuits are set up, one being induced by the fan 24 and consisting of a path between the absorber A₁ and the evaporator E, through the conduits 31 and 32 as described above, while the other is induced by the fan 52 and includes the absorber A₂, the boiler B₂, and the conduits 33, 34 and 35.

In a compound boiler system, the main boiler is normally maintained at a higher temperature than the auxiliary boiler. Inert gas is not intentionally present in the main boiler but is circulated through the auxiliary boiler. The boiler arrangement shown in Figure 5 is so constructed as to maintain the proper temperatures and heat inputs to the boilers. The construction is such that heat is transferred from the source in the flue 11 first to the liquid in the boiler B₁ and then to the liquid in the boiler B₂. By properly proportioning the areas of contact the proper gradient in temperature between the boilers B₁ and

B₂ can be maintained. At the same time, if the boiler B₂ is at a lower temperature and surrounds the boiler B₁ an economy in heat losses is effected, since the boiler B₂ acts as an insulation to some extent around the boiler B₁.

A compound refrigerating system in which two boilers are used but in which there is only one inert gas circuit, may be constructed in accordance with the present invention, as shown in Figure 6. In this embodiment the boiler construction may be identical to that shown in Figures 1 and 5. Likewise the rectifier, the condenser, the evaporator, and the pump may be the same and these elements are designated the same as the corresponding parts in Figure 1. Likewise the conduit which connects the boiler B₁ to the rectifier is designated 21, the conduit connecting the rectifier to the condenser 22, the conduit connecting the condenser to the evaporator 23, while the liquid conduits 36, 37 and 38 which may be identical in construction and function to those previously described in connection with Figure 1 have been similarly designated.

The absorber A of Figure 6 consists merely of a plain cylindrical vessel in which a number of 25 baffle plates 56 are provided, these baffle plates having openings 57 therein arranged in staggered relation. The lower part of the absorber may act as a reservoir for liquid.

An important feature of Figure 6 is the arrangement of the inert gas circuit. A gas conduit 58 connects the bottom of the evaporator E to the top of the absorber A. A second inert gas conduit 59 connects the bottom of the absorber A to the top of the boiler B₂. A third inert gas conduit 60 connects the bottom of the boiler B₂ to the pump P, and a fourth inert gas conduit 61 connects the pump P to the top of the evaporator E. With this construction the evaporator, absorber, boiler B₂ and pump are all connected in 30 series in so far as the inert gas circuit is concerned, the inert gas flowing downwardly from the top of the evaporator through the conduit 61, thence through the pump P, the conduit 60, upwardly through the boiler section B₂, and thence 40 through the conduit 59, the absorber, and back to the evaporator through the conduit 58.

While the inert gas is circulating as described above in the arrangement of Figure 6, the refrigerant may be caused to pass through two 50 cycles, one being from the boiler B₁ through the conduit 21, the rectifier R, the conduit 22, the condenser C where the refrigerant is liquefied, the conduit 23, the evaporator E, where it evaporates to produce a cooling effect and flows with 55 the inert gas through the conduit 61, then through the pump P, the auxiliary boiler B₂, and into the absorber where it will be absorbed by the absorption liquid and conveyed back to the boiler B₁ through the conduit 38, the rectifier R, and 60 the conduit 21.

A second refrigerant cycle consists in the evaporation or generation of vapor in the boiler B₂, its passage through the conduit 59 into the absorber where the vapor is absorbed and the return to the boiler B₂ through the conduit 38, the rectifier R, the pipe 21, the boiler B₁, and the conduit 47.

In the arrangement of Figure 6 the absorption liquid circulates exactly the same as in the 70 arrangement of Figure 1, and it will be unnecessary to repeat its cycle here.

An advantage of the arrangement of Figure 6 results from the fact that it is unnecessary to separate the absorber into two chambers. The 75

two inert gas circuits are combined and only one gas circulator is employed to circulate the gas through the various parts of the system in a single circuit. The arrangement of Figure 6 nevertheless provides means for gaining the advantages brought about by the use of the compound boiler. The refrigerant evaporates into the inert gas in the evaporator while this evaporator is at a low temperature. As the mixture of refrigerant and inert gas is conveyed through the boiler B₂, additional refrigerant is evaporated into the mixture from the solution in the boiler B₂, so that the mixture of gases flowing upwardly through the conduit 59 has a higher refrigerant content than that flowing downwardly through the conduit 61. If the absorber is adequately cooled, both the refrigerant which is evaporated in the evaporator and that which was generated in the boiler B₂ may be absorbed in the absorption liquid so that as it flows downwardly through the conduit 38 it is relatively rich. As this rich absorption liquid flows through the boiler B₁, the refrigerant is generated therefrom. In the boiler B₂, the solution which has been weakened in the boiler B₁ is further reduced to a lower refrigerant content, even though this vessel is at a lower temperature, since there is inert gas in the boiler B₂. The solution which flows from the boiler B₂ through the conduit 36 back to the absorber is thus brought to a very low degree of concentration so that as it comes in contact with the mixture of inert gas and refrigerant in the upper part of the absorber it may reduce the refrigerant content in the inert gas passing back to the evaporator through the conduit 58 to a very low degree.

It will be clear from what has been said above that in the arrangement of Figure 1, two separate inert gas circuits are provided, while in the arrangement of Figure 6, a single inert gas circuit is provided in a compound system. In accordance with still other embodiments of the invention, it is possible to devise inert gas circuits in which the evaporator, the absorber, and the auxiliary boiler are in series but in which the circuit to the auxiliary boiler is by-passed or shunted to a certain extent, so that more inert gas may circulate between the evaporator and the absorber than circulates between the evaporator, absorber and auxiliary boiler. Arrangements of this sort are shown in Figures 7 to 9.

In the arrangement of Figure 7 the boiler system, the rectifier, the condenser, and the evaporator are the same as that described in connection with Figures 1, 3, 4, 5 and 6 and are similarly designated. In this figure, the absorber is combined with the liquid and gas circulator into one structure, the arrangement being the same as that shown in Figure 11 of the co-pending application in the name of Curtis C. Coons and Arnold D. Siedle, entitled "Absorbers for refrigerating systems", Serial No. 23,628, filed May 27, 1935.

The main part of the absorber is shown in enlarged cross section in Figure 8. It may consist of a cylindrical vessel 62 having a number of baffle plates 63 therein each of which is provided with an opening surrounded by a depending flange 64. An electric motor 65 is mounted on the upper end of the vessel 62 and is adapted to drive a shaft 66 which extends longitudinally through it. The shaft carries a fan 67 near its upper end, and a number of agitators or splashing devices 68 at spaced points along its length, there being one splashing device 68 beneath each

of the depending flanges 64 on the baffle plates 63. Each splashing element is cup shaped as shown in Figure 8 so that the liquid which passes through the baffle plates 63 falls upon the inside of the splashing elements 68 and is thrown outwardly and around the interior surface of the vessel 62 as it travels downwardly through the absorber. The lower end of the shaft 66 carries a rotor 69 of a liquid pump which may be similar to that shown in Figure 4. The rotor is positioned between the end plate 70 of the absorber vessel and a plate 71 on the inside thereof, these plates cooperating to form a pump casing. The absorption liquid flowing down through the absorber vessel passes through a small opening 72 in the lower part of the plate 71 and is thrown outwardly through an outlet conduit connected to the vessel as will presently be described.

In addition to the main part 62 of the absorber, in the arrangement of Figure 7, there is an auxiliary absorber vessel 73, located some distance above the main vessel 62. The main vessel 62 is connected to this auxiliary vessel 73 by means of a liquid conduit 74 this conduit being connected to the lower part of the absorber vessel opposite the location of the rotor 69 of the liquid pump so that it acts as a discharge for this pump and conveys absorption liquid from the vessel 62 to the top of the vessel 73. From the vessel 73, the absorption liquid flows by gravity through the U-shaped pipe 75 into the rectifier R and from there through the conduit 21 to the main boiler B₁ from which it flows through the conduit 11 into the boiler B₂. After trickling downwardly over the baffle plates therein, the liquid flows thru a conduit 76 connected to the lower end of the boiler B₂ to the upper end of the inclined absorber 62. After flowing downwardly over the baffle plates in the absorber vessel 62 the liquid again enters the liquid pump casing through the opening 72 to complete its cycle. In case the liquid pump 69 pumps more liquid than necessary into the vessel 73, the excess may be returned to the absorber 62 through the overflow pipe 77. The conduit 77 may have a valve therein for controlling the flow of liquid therethrough, if desired. Certain portions of the conduits 75 and 76 may be in heat transfer relation and this may also be the case in connection with the conduits 76 and 77.

Any inert gas which may find its way into the vessel 73 may be discharged therefrom into the inert gas circuit through the conduit 78 connected to the inert gas system which will now be described.

The top of the absorber vessel 62 is connected to the bottom of the evaporator E by means of the inert gas conduit 79 while the top of the evaporator is connected to the bottom of the vessel 62 by the inert gas conduit 80, the conduits 79 and 80 being in heat exchange relation. At any convenient point in its path, the inert gas conduit 80 is provided with a restriction as shown at 81, and the gas conduits 82 and 83 are connected on the opposite sides of this restriction to provide a connection to the lower and upper ends respectively of the auxiliary boiler B₂. While a restriction is shown at 81, in the arrangement of Figure 7, it is obvious that a valve or other variable means may be used to vary the size of the restriction at this point. After the proper size has been determined by experimentation, a permanent restriction like that illustrated may be employed.

As shown in Figure 7, the gas conduits 82 and 83 may also be in heat exchange relation.

With the inert gas circuit constructed as described above, the inert gas may be caused to flow under the influence of the fan 67, driven by the motor 65 in the top of the vessel 62. The gas flows upwardly through the inert gas conduit 79 into the evaporator downwardly through the conduit 80, the restriction 81, and into the bottom of the vessel 62, and then upwardly therethrough to complete its cycle. At the same time, the inert gas will flow from the fan 67 upwardly through the conduit 79, the evaporator E, the upper part of the conduit 80, the conduit 82, into the boiler B₂, and after passing upwardly therethrough return to the absorber 62 through the conduit 83 and the lower part of the conduit 80. In the last mentioned inert gas circuit, the absorber 62, the evaporator E, and the boiler B₂ are connected in series as in the arrangement of Figure 6, but a portion of the inert gas is bypassed around the boiler B₂.

As in the arrangements of Figures 1 and 6 the refrigerant in the arrangement of Figure 7 passes through two cycles. Some refrigerant is generated in the boiler B₁, passes through the conduit 21, the rectifier R, the conduit 22, the condenser C, the conduit 23, the evaporator, where it produces a cooling effect, the inert gas conduit 80 and into the absorber 62 where it is absorbed, and flows back to the boiler B₁ through the conduits 74 and 75, the rectifier R and the conduit 21. At the same time, another amount of refrigerant is generated in the boiler B₂, flows through the inert gas conduit 83, the lower portion of the conduit 80, into the absorber 62 where it is absorbed and flows back to the boiler B₂ through the conduit 74, the vessel 73, the conduit 75, the rectifier R, the conduit 21, the boiler B₁ and the conduit 17.

Likewise, the arrangement of Figure 7 enables the absorption liquid supplied to the absorber to be brought to a low concentration, while that which leaves the absorber is at a high concentration, as in the arrangement of Figure 6. The absorption liquid flowing through the conduit 17 after considerable refrigerant has been expelled therefrom in the main boiler B₁, has its concentration further reduced in the boiler B₂ so that that which leaves the boiler B₂ through the conduit 76 has a very low concentration of refrigerant. It is thus possible to strip the inert gas flowing upwardly through the conduit 79 to the evaporator of its refrigerant content just before it leaves the absorber. On the other hand, the inert gas which enters the lower part of the absorber vessel 62 has a high refrigerant content, since it has been enriched in the boiler B₂. As this rich gas and absorption liquid come in contact in the lower part of the absorber 62, a high degree of concentration is reached and the liquid which flows through the conduits 74 and 75 back to the boiler system has a high concentration.

The advantage of the arrangement of Figure 7 over that of Figure 6 is that a proper degree of regulation of inert gas flow through the auxiliary boiler may be provided to obtain the best operating conditions.

An arrangement in which a compound boiler system employs an inert gas circuit similar to that described above in connection with Figure 7 is shown in Figure 9. In this figure, two absorbers are employed, and the two boilers B₁ and B₂ are separated although a single source of heat is employed to generate refrigerant in both of them.

In the arrangement of Figure 9, the boiler B₁ may consist simply of a cylindrical vessel ar-

ranged in a horizontal position and may be provided with a dome 84. A vapor lift pump conduit 85 is connected to the dome 84 and is adapted to convey liquid and refrigerant gas from the boiler B₁ into a small gas separation chamber 86 located 5 above the auxiliary boiler B₂.

The auxiliary boiler B₂ consists of a vertically disposed cylindrical vessel having a flue 87 extending vertically thereto, and a number of baffle plates 88 therein. The gas separation chamber 10 86 is connected to the boiler B₂ by a U-shaped conduit 89 forming a liquid seal.

The heating flue used to supply heat to the boiler B₁ as shown at 90, has one end connected to a chimney 91 which passes up vertically and 15 surrounds the auxiliary boiler B₂. Thus when heat is supplied to the boiler B₁ by a suitable source located in the heating tube 90, the gases of combustion or heated air may also pass upwardly through the chimney 91 and convey some heat 20 to the auxiliary boiler B₂, the flue 87 in the boiler B₂ aiding in transferring the heat from the chimney gases to the boiler B₂.

The gas separation chamber 86, located on the top of the boiler B₂, is connected by means of a 25 conduit 92 to a rectifier R, which is in turn connected by the conduit 93 to a condenser C adapted to feed liquified refrigerant to the evaporator through the conduit 94.

It should be noted that the gas separation 30 chamber 86 is independent of the main portion of the boiler B₂. There is no inert gas in the chamber 86.

Absorption liquid pumped into the chamber 86 by the gas lift pump 85 flows through the liquid 35 seal device 89, and trickles downwardly through the boiler B₂. It then flows through the conduit 95 which connects the boiler B₂ to the absorbers, there being a liquid divider or T-connection 96 to cause some absorption liquid to flow into the 40 conduit 97 leading to the absorber A₂ while another portion flows through the conduit 98 into the absorber A₁.

The absorber A₂ consists of a vertically disposed cylindrical vessel having electric motor 99 45 mounted on the top thereof, and adapted to drive a gas fan 100 which is located in its upper part. The fan causes circulation of inert gas to both of the absorbers A₁ and A₂, and also the evaporator E and the boiler B₂ as will presently be described. 50

The absorption liquid supplied to the absorber A₂ trickles downwardly over baffle plates 101 therein, and then flows into the lower part of the absorber A₁ through the conduit 102 which has a U-bend therein to provide a liquid seal. The 55 absorption liquid which flows into the absorber A₁ through the pipe 98 trickles downwardly over baffle plates 103 therein and joins the absorption liquid entering this vessel through the conduit 102 and flows back to the boiler 1 through the 60 liquid conduit 104. The conduits 104 and 95 may be in heat exchange relation as illustrated.

The inert gas circuit of Figure 9 includes a gas conduit 105 connecting the top of the absorber A₂ to the bottom of the evaporator E. A second 65 inert gas conduit 106 connects the top of the evaporator to the bottom of the absorber A₁. This conduit has a restriction therein as shown at 107 and two inert gas conduits 108 and 109 are connected to thereto the opposite sides of 70 the restriction, the conduit 108 being connected to the lower part of the boiler B₂ and the conduit 109 connected to the upper part thereof. The conduits 108 and 109 are in heat exchange relation. In addition to the inert gas conduits men- 75

tioned above, another conduit 110 connects the top of the absorber A₁ to the bottom of the absorber A₂.

The inert gas conduits of the arrangement of Figure 9 are the same as those in Figure 7 except that the inert gas, rich in refrigerant, coming into the absorber system through the conduit 106, first passes in contact with comparatively strong solution in the lower part of the absorber A₁, and then in contact with weaker solution in the upper part of the absorber A₁, so that when it flows to the absorber A₂ through the conduit 110, the refrigerant content therein has already been materially reduced. As it passes upwardly through the absorber A₂ in contact with the weak absorption liquid entering this vessel through the conduit 97, the inert gas is stripped or reduced to a low refrigerant content and then expelled from the absorber A₂ by means of the fan 100.

It will also be noted that there is no power driven liquid pump in the arrangement of Figure 9, the gas lift pump 85 being used in place thereof. Except for the use of two absorbers and the differences in the boiler system and the liquid pumping means, the system of Figure 9 is similar to that of the other figures and can be readily understood by those skilled in the art, without repeating the paths for the flow of the fluids.

While only a few embodiments of the invention have been shown and described herein it is obvious that various changes may be made without departing from the spirit of the invention or the scope of the annexed claims.

I claim:

1. Compound absorption refrigerating apparatus using inert gas and including an evaporator, an absorber, an inert gas charged boiler and means for circulating the inert gas in a circuit through said evaporator, boiler and absorber with more inert gas passing through the evaporator than through the gas charged boiler, the arrangement being such that refrigerant is added to the inert gas in the evaporator, more refrigerant added to the inert gas in the boiler, and the refrigerant added to the inert gas both in the evaporator and boiler removed therefrom in the absorber.

2. Compound absorption refrigerating apparatus using inert gas and including an evaporator, an absorber, an inert gas charged boiler, inert gas conduits connecting the evaporator and the absorber, and means connected in parallel with a portion of one of said conduits for circulating inert gas through said gas charged boiler.

3. Compound absorption refrigerating apparatus using inert gas and including an evaporator, an absorber, an inert gas charged boiler, inert gas conduits connecting the evaporator and absorber, one of said conduits having a restriction therein and gas conduits connecting the gas charged boiler to the conduit on the opposite sides of said restriction, the arrangement being such that some inert gas may flow in series between the evaporator, boiler and absorber while other gas flows between the evaporator and absorber by-passing the boiler.

4. Compound absorption refrigerating apparatus using inert gas and including an evaporator, two absorbers, an inert gas charged boiler, means for supplying weak absorption liquid to both absorbers, means for circulating inert gas through the evaporator the gas charged boiler and the absorbers in series, the arrangement

being such that there is provision for by-passing some gas around said boiler.

5. In continuous absorption refrigerating apparatus, a boiler system comprising a heating flue, a boiler surrounding said heating flue and a second boiler surrounding said first mentioned boiler, the arrangement being such that heat is transferred from said heating flue to said first mentioned boiler and from said first mentioned boiler to said second mentioned boiler and means responsive to a high temperature in said first boiler operative to circulate fluid therefrom into said second boiler.

6. In continuous absorption refrigerating apparatus using inert gas, a compound boiler system comprising a heating flue, a main boiler surrounding said heating flue, an auxiliary boiler surrounding said main boiler, means for circulating absorption liquid through said main boiler and said auxiliary boiler in series and in the order named and means for circulating inert gas through said auxiliary boiler.

7. In continuous absorption refrigerating apparatus, using inert gas, a compound boiler system comprising a main boiler for generating a first body of refrigerant, means for discharging said refrigerant from the boiler system, an auxiliary boiler for generating a second body of refrigerant, means using a single source of heat for heating said boilers, means for circulating absorption liquid through said main boiler and said auxiliary boiler and means for circulating inert gas through said auxiliary boiler to remove said second body of refrigerant, the arrangement being such that heat is transferred from the source of heat to said main boiler and from said main boiler to said auxiliary boiler.

8. In continuous absorption refrigerating apparatus, a compound boiler system comprising three concentrically disposed cylinders having their ends connected by annular end plates so as to form two chambers concentrically disposed around a centrally located passage adapted to act as a heating flue for transferring heat from a fluid therein to the inner concentric chamber and from the inner concentric chamber to the outer concentric chamber and means responsive to a high temperature in the inner of said chambers and operative to transfer fluid therefrom to the outer of said chambers.

9. Compound absorption refrigerating apparatus using inert gas and including an evaporator, an absorber, an inert gas charged boiler, inert gas conduits connecting the evaporator and absorber affording a circuit for the passage of gas through said absorber and evaporator in series, and means connected in parallel with a portion of said circuit for circulating inert gas through said gas charged boiler.

10. An absorption refrigerating apparatus containing a pressure equalizing gas and operating at three temperature ranges, namely, a relatively high temperature range of heat input, a relatively low temperature range of heat input and an intermediate temperature range of heat rejection, said apparatus including a plurality of vessels operating in said low and intermediate temperature ranges, means affording a complete cycle of circulation of said pressure equalizing gas through said vessels and conduits connected to a portion of said means whereby a portion of the gas is by-passed through a vessel operating in the higher temperature range.

11. The method of producing refrigeration in an absorption refrigeration system of the type

using a refrigerant, an absorbent therefor, and a pressure equalizing medium comprising applying heat to two bodies of rich absorbent in liquid communication, condensing the refrigerant liberated by one of said bodies, allowing said refrigerant to evaporate into a pressure equalizing medium to produce refrigeration, conveying the mixture thus formed into contact with said second body of absorbent whereby additional refrigerant is liberated and conducting the newly formed mixture into intimate contact with lean absorbent derived from at least one of said bodies whereby the refrigerant is absorbed.

12. The method of producing refrigeration in an absorption refrigeration system of the type using a refrigerant, an absorbent therefor, and a pressure equalizing medium comprising raising the temperature of two bodies of rich absorbent in liquid communication to liberate refrigerant, condensing the refrigerant from one of said bodies, allowing said refrigerant to evaporate into a pressure equalizing medium to produce refrigeration, and passing the mixture so formed into intimate contact with lean absorbent after by-passing a portion of the mixture into contact with the other body of absorbent whereby additional refrigerant is liberated by said second body of absorbent, and substantially all the refrigerant liberated from both bodies is subsequently absorbed.

13. The method of reducing the concentration of the absorbent medium in the generator of an absorption refrigeration system which comprises applying heat to absorbent to liberate a medium contained therein, passing the partially deconcentrated absorbent into another zone, applying heat thereto without increasing the temperature of the absorbent, and passing an inert gas under pressure over the absorbent whereby the concentration of the absorbent is further reduced.

14. The method of reducing the concentration of the absorbent medium in the generator of a closed absorption refrigeration system employing a refrigerant, an absorbent therefor, and an inert gas, which comprises applying heat to the absorbent to liberate a refrigerant, passing the partially deconcentrated absorbent into the presence of the inert gas where additional refrigerant is liberated without increasing the temperature of the absorbent or reducing the total pressure in the system.

15. The method of reducing the concentration of the absorbent in the generator of a closed absorption refrigeration system employing a refrigerant, an absorbent therefor, and an inert gas, which comprises applying heat to rich absorbent to liberate refrigerant and passing the partially deconcentrated absorbent into the presence of inert gas while maintaining the absorbent in heat exchange relation with said heated rich absorbent whereby the concentration of the absorbent is further reduced in the presence of the same total pressure and without increasing the temperature of the absorbent.

16. The method of reducing the concentration of the absorbent in the generator of a closed absorption refrigeration system employing a refrigerant, an absorbent therefor, and a pressure equalizing medium, which comprises applying heat to rich absorbent to liberate substantially all the refrigerant possible under the prevailing temperature and pressure conditions, and passing the partially deconcentrated absorbent into the presence of the pressure equalizing medium while maintaining the same in heat exchange

relation with the heated absorbent whereby the concentration of the absorbent is further reduced in the presence of the same total pressure and at a lower temperature than would otherwise be possible.

17. The method of reducing the concentration of the absorbent in the generator of a closed absorption refrigeration system employing a refrigerant, an absorbent therefor, and a pressure equalizing medium, which comprises applying the heat of a burning flame to rich absorbent to liberate refrigerant, passing the partially deconcentrated absorbent into the presence of a pressure equalizing medium, and continuing to heat said last mentioned absorbent by the products of combustion from said flame whereby additional refrigerant is liberated in the presence of the same total pressure and without increasing the temperature of the absorbent.

18. The method of reducing the concentration of the absorbent in the generator of a closed absorption refrigeration system employing a refrigerant, an absorbent therefor, and an inert gas, which comprises applying heat to rich absorbent to liberate refrigerant, passing the partially deconcentrated absorbent into the presence of an inert gas, and liberating additional refrigerant into the inert gas by subjecting the last mentioned absorbent to waste heat from said first mentioned rich absorbent.

19. The process of producing refrigeration in a closed absorption refrigeration system employing a refrigerant, an absorbent therefor, and a pressure equalizing medium, which comprises applying heat to rich absorbent to liberate refrigerant, condensing the refrigerant, permitting the refrigerant to evaporate into an equalizing medium to produce refrigeration, conducting one portion of the mixture so formed over partially deconcentrated absorbent whereby additional refrigerant is liberated, recombining the two portions of the mixture, then conducting the mixture into intimate contact with the lean absorbent whereby the refrigerant is absorbed, and then returning the equalizing medium to the evaporating zone and the enriched absorbent to the heating zone in order that the process may be repeated continuously.

20. The process of producing refrigeration in a closed absorption refrigeration system employing a refrigerant, an absorbent therefor, and a pressure equalizing medium, which comprises applying heat to rich absorbent to liberate refrigerant, condensing the refrigerant, permitting the refrigerant to evaporate into an equalizing medium to produce refrigeration, conducting one portion of the mixture so formed over partially deconcentrated absorbent to liberate additional refrigerant without increasing the temperature of the absorbent, dividing the lean absorbent into a plurality of bodies, recombining the two portions of the mixture, passing the mixture in series into intimate contact with first one body of absorbent and then with another, to separate the two constituents thereof, and returning the equalizing medium to the evaporating zone and the two bodies of enriched absorbent to the heating zone.

21. The process of producing refrigeration in a closed absorption refrigeration system employing a refrigerant, an absorbent therefor, and a pressure equalizing medium, which comprises applying heat to rich absorbent to liberate refrigerant, condensing the refrigerant, permitting the refrigerant to evaporate into an equalizing

medium to produce refrigeration, dividing a stream of deconcentrated absorbent into a plurality of streams, passing the mixture formed in the evaporating zone in series and in counterflow to first one of said streams and then another, after first by-passing part of the mixture over the partially deconcentrated absorbent to liberate additional refrigerant, and returning the equalizing medium to the evaporating zone and 10 the enriched absorbent to the heating zone whereby the above cycle may be repeated continuously.

22. The process of producing refrigeration in a closed absorption refrigeration system employing a refrigerant, an absorbent therefor, and a pressure equalizing medium, which comprises applying heat to rich absorbent to liberate refrigerant, condensing the refrigerant, permitting the refrigerant to evaporate into an equalizing 20 medium to produce refrigeration, passing part of the gaseous mixture so formed over the partially deconcentrated absorbent to liberate additional refrigerant, dividing a stream of the deconcentrated absorbent into two gravity actuated 25 streams, passing all of the gaseous mixture in intimate contact with and in counterflow to first one stream of absorbent to remove refrigerant therefrom, and then in intimate contact with and in counterflow to the other stream of absorbent to strip the remaining refrigerant from 30 the mixture, dissipating the endothermic heat of absorption to a cooling medium, and returning the equalizing medium to the evaporating zone and the enriched absorbent to the heating zone in order that the process may be repeated continuously.

23. The process of producing refrigeration in a closed absorption refrigeration system employing a refrigerant, an absorbent therefor, and a pressure equalizing medium which comprises applying heat to rich absorbent to liberate refrigerant, condensing the refrigerant, permitting the refrigerant to evaporate into an equalizing medium to produce refrigeration, by-passing part of the gaseous mixture so formed over the partially deconcentrated absorbent to liberate additional refrigerant, forcibly circulating the deconcentrated absorbent over a circuit having at least two parallel legs therein, forcibly circulating all of said gaseous mixture, including said by-passed portion, first into intimate contact with the absorbent in one of said legs, and then in intimate contact with the absorbent in another leg and then back to the evaporating zone.

24. The process of producing refrigeration in a closed absorption refrigeration system employing a refrigerant, an absorbent therefor, and a pressure equalizing medium, which comprises applying heat to rich absorbent to liberate refrigerant, condensing the refrigerant, permitting the refrigerant to evaporate into an equalizing medium to produce refrigeration, by-passing part of the gaseous mixture so formed over the partially deconcentrated absorbent to liberate additional refrigerant, circulating the deconcentrated absorbent over a circuit having at least two legs therein, circulating all of said gaseous mixture including said by-passed portion in series and in intimate contact with the absorbent in one of said legs, and then in intimate contact with the absorbent in another leg, and then back to the evaporating zone, both of said fluids being circulated con-currently and forcibly circulated.

25. A compound boiler for use in an absorption refrigeration apparatus comprising a chamber having a partition dividing the same into two sections, a heating flue passing through one of said sections for the purpose of transmitting heat directly to liquid in one section and indirectly to fluid in the other section, means operable to transfer liquid from the directly heated section to the other section, and means for circulating an inert gas through the indirectly heated section.

26. A compound boiler for use in an absorption refrigeration apparatus comprising a first liquid chamber and a second liquid chamber, means to directly heat one chamber, and to indirectly heat the other chamber, means operable to transfer partially deconcentrated liquid from said first chamber to said second chamber in response to the heating of one of said chambers, and means for circulating a gas through said second chamber.

27. A compound still for use in separating two liquids in solution having different boiling points, comprising a first chamber and a second chamber, means for directly heating said first chamber and for heating said second chamber by heat not retained by the first chamber, a series of liquid dispersing members in the second chamber, means for transferring partially deconcentrated liquid from said first chamber to the liquid dispersing members in said second chamber, and means for passing an inert gas in intimate contact with the liquid in the second chamber whereby the liquid is further deconcentrated.

28. A compound still for use in separating two liquids in solution having different boiling points, comprising a first liquid chamber, a flue having a portion thereof in heating relation to said chamber, a second chamber within said flue and positioned above said first chamber, heating means at the lower end of the flue, means to transfer partially deconcentrated liquid from said first chamber to the second chamber, and means for passing an inert gas in intimate contact with the liquid in the second chamber whereby the concentration of the liquid is further reduced.

29. In an absorption refrigerating apparatus, a compound boiler system comprising a main boiler and an auxiliary boiler, means for causing the auxiliary boiler to operate at a lower refrigerant pressure than said main boiler, and means for heating said boilers, said heating means including a heating source located near the main boiler and means for transferring heat from said source to said auxiliary boiler, the arrangement being such that said auxiliary boiler may operate at a lower temperature than said main boiler.

30. In an absorption refrigerating apparatus using inert gas, a compound boiler system comprising a main boiler, an auxiliary boiler, means using a single source of heat for heating said compound boiler, means for circulating the absorption liquid through said main boiler and said auxiliary boiler and means for circulating inert gas through said auxiliary boiler, the arrangement being such that a fluid, such as air, is heated by said source of heat and passed first in contact with said main boiler and then in contact with said auxiliary boiler, thereby heating both of said boilers.

CURTIS C. COONS.

CERTIFICATE OF CORRECTION.

Patent No. 2,178,560.

November 7, 1939.

CURTIS C. COONS.

It is hereby certified that error appears in the printed specification of the above numbered patent requiring correction as follows: Page 1, second column, line 53, for the word "holder" read boiler; page 6, second column, line 67, claim 10, for "intermediate" read intermediate; page 7, first column, line 25, claim 12, before "by-passing" insert first; and that the said Letters Patent should be read with this correction therein that the same may conform to the record of the case in the Patent Office.

Signed and sealed this 26th day of December, A. D. 1939.
